UNITED STATES PATENT OFFICE.

FRANK L. WRIGHT, OF CHICAGO, ILLINOIS, ASSIGNOR TO THE LUXFER
PRISM PATENTS COMPANY, OF SAME PLACE.

DESIGN FOR A PRISM-PLATE.

SPECIFICATION forming part of Design No. 27,993, dated December 7, 1897.

Application filed October 20, 1897. Serial No. 655,851. Term of patent 14 years.

To all whom it may concern:

Be it known that I, FRANK L. WRIGHT, a citizen of the United States, residing at Chicago, in the county of Cook and State of Illinois, have invented a certain new and original Design for Prism-Plates, of which the following is a specification.

My invention relates to a new and original design for prism-plates, and is illustrated in the accompanying drawings, wherein—

Figure 1 is a view of a prism-plate embodying my invention. Fig. 2 is a section through Fig. 1 on line 2 2.

A is a prism-plate having on one side the prisms B B and on the other side the lines of separation C C, which separate the surface into a series of distinct areas. D D are pat-

terns of ornamentation on each of these separate areas, constituting a separate, distinct, and complete design on each of such areas. 20

The essential features of my design are found in a prism-plate having prisms on one side and on the other a series of lines of separation which divide the surface of the plate into a series of uniform areas, and a series of 25 complete, distinct, and separate ornamental patterns, one on each such surface area.

I claim—

A design for a prism-plate, substantially as shown and described.

FRANK L. WRIGHT.
